ROLLER BEARING ASSEMBLING MACHINE

Frank Ketcham, Dearborn, and George E. Dunn,
Detroit, Mich., assignors to Universal Products
Co., Inc., a corporation of Delaware

Original application March 30, 1933, Serial No.
663,444. Divided and this application Septem-
ber 30, 1935, Serial No. 42,766

14 Claims. (Cl. 198—218)

This invention relates to machines for assembling roller bearings or the like, and it has particular relation to the mechanism by which rollers are advanced from a suitable hopper mechanism to the device by which they are assembled in a bearing. This application constitutes a division of our co-pending application for patent, Serial No. 663,444, filed March 30, 1933, and of our co-pending application for patent, Serial No. 707,289, filed January 19, 1934. These applications have matured into Patents 2,031,417 dated Feb. 18, 1936, and 2,068,683 dated Jan. 26, 1937, respectively.

It is an object of the present invention to provide an improved mechanism adapted to feed a series of rollers axially, and then align and feed them transversely of their axes in a suitable condition for assembly in a roller bearing structure.

An important feature of the invention resides in the provision of a novel pushing means designed to prevent damage to the machine or rollers in the event of improper feeding of the rollers, and to prevent clogging of rollers in the machine.

Other objects of the invention will become apparent from the following description, the drawings relating thereto and the claims hereinafter set forth.

For an understanding of the invention, reference may be had to the drawing, wherein:

Figure 1 constitutes a cross section of a portion of the machine showing the improved pusher mechanism in elevation;

Fig. 2 is a side elevation of the pusher structure shown in Fig. 1;

Fig. 3 is a partial section taken on the line 3—3 of Fig. 1.

For a full description of the complete machine and the manner in which the improved feeding mechanism of this application cooperates therewith, reference may be had to our co-pending application, Serial No. 663,444, aforementioned.

In the construction shown in the drawing, the improved machine is assembled on a frame including a horizontally disposed plate 15. Secured to the plate is an upstanding bracket 55 which carries on its top face a block 56, secured thereto by screws 57. As shown in Fig. 3, one side edge of block 56 is bored to receive a conduit 45. The interior of this conduit communicates with a slot 160 formed in the end of block 56; and the opposite side of slot 160 contains a tapped hole closed by a suitable plug 161. This hole is located in alignment with the central

opening in conduit 45. The width of the slot in block 56 corresponds to the length of the rollers which the machine is to assemble, and it is adapted to receive the rollers indicated at 52, as they are delivered from conduit 45. Slot 160 in block 56 communicates with a groove 113 in the left hand face of bracket 55 as viewed in Fig. 1. This groove forms three sides of a vertical passageway for the reception of a column of transversely aligned rollers 52, the fourth side of passageway 113 being formed by the face of a block 102 which is secured to bracket 55 by studs 103. The top of bracket 55 adjacent this passageway is recessed to receive a block 88 which lies flush with the top surface of bracket 55, and is provided with a V-edge formed by oppositely disposed bevels adjacent the passageway. Movable plates 90 and 104 mounted adjacent the top surface of block 102 form a variable capacity reservoir 101 for the reception of excess rollers fed to the assembly devices, all as described in the aforementioned co-pending application.

As the result of this structure, there is provided a horizontal conduit 45 communicating with a vertical passageway 113 which conducts the rollers to the assembling mechanism indicated generally at 162. The communicating reservoir 101 which joins passageway 113 at the apex of block 88 receives the temporary excess of rollers caused by the intermittent action of the assembling mechanism. These and other features of our machine are claimed in one or another of our previously mentioned co-pending applications; and it is the purpose of this application to cover our improved pusher mechanism by means of which rollers received axially from conduit 45 are advanced transversely into the vertical passageway 113 above the juncture of reservoir 101 therewith.

This mechanism comprises a pair of depending fingers 58 and 59 which are rigidly secured to the ends of horizontally disposed rocker arms 60 and 61, respectively, which are journaled on a cross shaft 62. The shaft 62 is supported by an upstanding bracket 63, the lower end of which is rigidly mounted on the top plate 15, and the upper end of which is bifurcated to form spaced parallel arms 64 and 65, which receive the rocker arms therebetween, and in the upper ends of which the shaft 62 is supported.

The rocker arms 60 and 61 are adapted to have individual and independent movements from a single or common source of actuation. This is accomplished by the provision of a transversely disposed yoke member 66, which is piv-

oted medially of its ends on a pin 67, the ends of the yoke arm being bifurcated so as to be of upstanding U-shape to embrace horizontally disposed, rigidly mounted pins 68 and 69 mounted in the ends of rocker arms 60 and 61 respectively, which ends are opposite to the ends having the fingers 58 and 59.

The yoke member 66 is pivoted to the upper end of a push rod 70, the lower end of which 10 is threaded to receive a pair of nuts 71 and axially bored to receive the upper end of an axially disposed, downwardly projecting pin 72. The lower end of pin 72 is slidably received in an axially disposed bore 73 of a push rod 74. 15 The push rods 70 and 74 are normally held in a spaced relation, as shown in Figures 1 and 2 of the drawing, by a helical compression spring 76, the upper end of which surrounds the lower end of push rod 70 and bears against the adjusting nut 71, and the lower end of which 20 similarly surrounds the upper end of push rod 74 and bears against a nut 77 which is threaded on the top end thereof.

Axial movement is imparted to the two part 25 push rod assembly in an upward direction by cam 78 which is fixed to a horizontally journaled countershaft 79. The shaft and cam are rotated continuously by any suitable means, such as that shown in our parent application.

30 The push rod and rocker arms are normally yieldingly urged downward by helical tension springs 80 and 81, the upper ends of which are attached to the pins 68 and 69, respectively, and the lower ends of which are anchored to the 35 horizontally disposed brackets 82 and 83, which are integrally formed on the bifurcated ends 64 and 65, respectively, of the supporting bracket 63.

In operation, rollers are fed axially through 40 conduit 45 by any suitable means, such as the hopper mechanism disclosed in our parent application. As they leave conduit 45, they pass into slot 160 in block 58 immediately below the two pusher elements 58 and 59, and come to 45 rest upon the stack of rollers 52 which normally fills passage 113. As rod 70 is reciprocated by cam 78 through spring 76, the two pusher elements are forced downwardly upon the stack of rollers, thereby advancing the entire series in passageway 113. The moving parts of the 50 machine are so timed that normally the pusher elements are advanced in timed relation with the feed of rollers from conduit 45, and this step-by-step movement of the rollers in passageway 113 is carried on continuously during normal 55 operation of the machine.

The spring 76 in the pusher rod assembly is provided to prevent injury to the rollers or feeding mechanism in the event of jams in the roller passageway or conduit. This spring has 60 sufficient stiffness, however, to advance the roller column during normal operation.

In the event that one of the rollers should 65 not be projected completely into the slot 160 from the discharge conduit 45, pressure finger 59 would be blocked against downward movement. Under these circumstances, however, due to the equalizer connections 67 and 66 etc., between the push rod and the rocker arms, pressure element 58 is free to move downwardly independently of member 59, thereby preventing the application of the full compressive force of spring 76 on the projecting end of the roller by means of pressure element 59. As a result of this construction a stronger spring 76 can be 70 used than otherwise would be possible without 75

injury to either the partially ejected roller or the conduit 45.

It will be noted that the roller contacting surface on element 59 is substantially greater than that on member 58, with the result that 5 the roller must be almost free of the conduit 45 before it is engaged by pressure element 58. This is of advantage since, when the pressure member 59 engages a partially ejected roller, member 58 will move downwardly and block the 10 complete discharge of that roller from the conduit. This insures that on the next and subsequent operations of the pressure members the rollers will be completely discharged from the conduit, and it prevents the repeated discharge 15 of a roller under axial pressure in the conduit 45, after the pressure element has started to apply pressure to the column in passageway 113.

Although but one specific embodiment of this invention has been herein shown and described, 20 it will be understood that numerous details of the construction shown may be altered or omitted without departing from the spirit of this invention as defined by the following claims.

We claim:

1. In a roller bearing assembling machine, 25 means for supplying rollers, a duct communicating with said means for receiving rollers discharged therefrom, the duct having a longitudinally extending slot therethrough, a pair of pusher fingers extending into the slot for ejecting rollers from the duct, independent arms for actuating the pusher fingers, a link pivotally connecting the arms, and an actuating rod connecting the link intermediate the point of connection of the arms.

2. In a roller bearing assembling machine, 40 means for supplying rollers, a duct communicating with said means for receiving rollers discharged therefrom, the duct having a longitudinally extending slot therethrough, a pair of pusher fingers extending into the slot for ejecting rollers from the duct, independent arms for actuating the pusher fingers, a link pivotally connecting the arms, a two piece actuating rod 45 connected to the link intermediate the point of connection of the arms, and yielding means interposed between the two parts of the rod.

3. A feed mechanism for a roller bearing assembling machine comprising, means for guiding 50 a plurality of transversely aligned rollers, a pair of pusher members extending into said guiding means and adapted to engage a roller positioned therein, and means for actuating said pusher members to effect advance of said rollers in said guide means, said means being so constructed and arranged as to permit one of said members to move independently of the other.

4. A feed mechanism for a roller bearing assembling machine comprising, means for guiding 60 a plurality of transversely aligned rollers, a pair of pusher members extending into said guiding means and adapted to engage a roller positioned therein, and means for resiliently actuating said pusher members to effect advance of said rollers 65 in said guide means, said means being so constructed and arranged as to permit one of said members to move independently of the other.

5. A feed mechanism for a roller bearing assembling machine comprising, means for guiding 70 a plurality of transversely aligned rollers, a pair of pusher members extending into said guiding means and adapted to engage a roller positioned therein, a push rod, means to reciprocate said push rod, and an equalizer connection between 75

said pusher members and said push rod whereby upon reciprocation of said rod one of said members may advance independently of the other.

6. A feed mechanism for a roller bearing assembling machine comprising, means for guiding a plurality of transversely aligned rollers, a pair of pusher members extending into said guiding means and adapted to engage a roller positioned therein, a push rod having a resiliently compressible section, means to reciprocate said push rod, and an equalizer connection between said pusher members and said push rod, whereby upon reciprocation of said rod one of said pusher members can advance independently of the other.

15 7. A feed mechanism for a roller bearing assembling machine comprising, means for guiding a plurality of transversely aligned rollers, a pair of pusher members extending into said guiding means and adapted to engage a roller positioned therein, a pair of rocker arms having one end of each operatively connected to said pusher members respectively, a push rod having a resiliently compressible section, means to reciprocate said rod, and a link engageable at its 25 ends with the free ends of said rocker arms and pivotally secured intermediate its ends to said push rod.

8. A feed mechanism for a roller bearing assembling machine including a passageway adapted to guide rollers in transverse alignment, and a pusher mechanism comprising a pair of pusher elements extending into said passageway and engageable with the roller bearing positioned therein, said elements having combined roller contacting faces substantially co-extensive with the width of said passageway, and means for advancing said elements, said means being so constructed and arranged as to permit one of said elements to advance independently of the other.

40 9. A feed mechanism for a roller bearing assembling machine including means for receiving and guiding a plurality of rollers in transverse alignment, means for feeding rollers axially to said guide means, means to move rollers transversely along said guide means comprising a pair of pusher elements adapted to engage the rollers as they are received by said guide means from said feeding means, and means for advancing said elements, said means being so constructed 50 and arranged as to permit one of said elements to move independently of the other.

10. A feed mechanism for a roller bearing assembling machine comprising, means to supply a plurality of rollers in end to end relation, guide means positioned transversely with respect to said means and adapted to receive rollers therefrom and guide them in transverse alignment, a pusher mechanism positioned adjacent the receiving end of said guide means and adapted to advance said 55 rollers along said guide means, said pusher mechanism comprising a pair of roller engaging devices, and means for advancing said devices, said means being so constructed and arranged as to permit the advance of one of said devices independently of the other.

11. A feed mechanism for a roller bearing assembling machine including, a passageway adapted to receive and guide rollers in transverse alignment, means adjacent one end of said passageway

way for feeding rollers axially thereof into said passageway, and a pusher mechanism for advancing said rollers in said passageway as they are received from said feeding means, said pusher mechanism comprising a pair of pusher elements 5 adapted to engage a roller positioned in said passageway, a push rod including a resiliently compressible section, means for reciprocating said push rod, and means connecting said push rod with said pusher elements including an equalizer 10 mechanism whereby one of said elements may advance independently of the other.

12. A feed mechanism for a roller bearing assembling machine including, a passageway adapted to receive and guide rollers in transverse alignment, means including a conduit arranged transversely with respect to said passageway for ejecting rollers axially thereof into said passageway, a feed member adapted to engage and advance rollers transversely in said passageway, an actuating member for said feed member, a reciprocating means, resilient means connecting said reciprocating means with said actuating member, and means connecting said actuating member and feed member adapted when said feed member engages a partially ejected roller to permit movement of said actuating member in response to reciprocations of said reciprocating means without moving said feed member to prevent the building up of an excess pressure on said roller. 30

13. A feed mechanism for a roller bearing assembling machine including, a passageway adapted to receive and guide rollers in transverse alignment, means engaging one end of said passageway for feeding rollers axially thereof into said 35 passageway, a pusher mechanism for advancing said rollers in said passageway as they are received from said feeding means, said pusher mechanism comprising a pair of pusher elements 40 adapted to engage a roller positioned in said passageway, a push rod including a resiliently compressible section, means for reciprocating said push rod, a pair of rocker arms connected respectively at one end to each of said pusher elements, and a link pivoted intermediate its ends on said 45 push rod and engaged at each end respectively with the free ends of said rocker arms.

14. A feed mechanism for a roller bearing assembling machine including, a passageway adapted to receive and guide rollers in transverse 50 alignment, means adjacent one end of said passageway for feeding rollers axially thereof into said passageway, and a pusher mechanism for advancing said rollers in said passageway as they are received from said feeding means, said pusher 55 mechanism comprising a pair of pusher elements extending into said passageway and adapted to engage a roller positioned therein at axially spaced points, said elements having combined roller engaging surfaces substantially equal in 60 width to the width of said passageway, and the element adjacent the side of the passageway from which the rollers are received having a contacting face of greater width than that of the other element, and resilient means for advancing said 65 elements.
